CLAIM

The ornamental design for a combination carry, storage and display case for dolls and toys, as shown and described.

DESCRIPTION

FIG. 1 is a perspective view of the combination, carry, storage and display case for dolls and toys in an open position with a doll compartment removed and a storage lid removed.

FIG. 2 is a back view of the case in a closed position.

FIG. 3 is a front view of the case in a closed position.

FIG. 4 is a left end view of the case in a closed position.

FIG. 5 is a perspective view of the case in a partially opened position; and,

FIG. 6 is a perspective view of the case in a closed position. While a right end view of the case in a closed position is not shown, the right side of the case is a mirror image of the left side, wherein the left side is shown in FIG. 4.
